INVENTOR
Robert M. Ostrander,
Munn & Co.
ATTORNEY

UNITED STATES PATENT OFFICE.

ROBERT M. OSTRANDER, OF LOS ANGELES, CALIFORNIA.

MATCH-BOX HOLDER.

Application filed June 15, 1927. Serial No. 199,005.

My invention relates to match box holder and has for its purpose the provision of a holder of extremely simple, inexpensive and suitable construction, which is capable of being readily applied to the steering wheel of an automobile so as to be within convenient reach of the operator to permit the withdrawal and lighting of matches for lighting cigarettes, cigars and the like.

10 It is also a purpose of my invention to provide a match box holder as an advertising novelty, the holder accommodating an advertising card in addition to the match box which is in full view of the operator of the 15 vehicle when the holder is in applied position upon the steering wheel.

I will describe only one form of match box holder embodying my invention, and will then point out the novel features thereof in 20 the claim.

In the accompanying drawings:

Fig. 1 is a view showing in top plan one form of match box holder embodying my invention in applied position to a steering 25 wheel;

Fig. 2 is a view showing the holder in bottom plan and in applied position to the steering wheel spoke;

Fig. 3 is a transverse sectional view taken 30 on the line 3—3 of Fig. 2; and

Fig. 4 is a detail view showing the match box holder in perspective.

Fig. 5 is a sectional view taken on line 5—5 of Fig. 1.

35 Referring specifically to the drawings, my invention in its present embodiment comprises a container of rectangular form and of a size to receive the conventional pocket size match box. The container is formed of any 40 suitable material, preferably rubber. The bottom wall 15 of the container is provided with companion attaching flanges 16 preferably formed integral with the container and hence, of the same material. They are disposed in converging relation to each other along their lines of connection with the back of the container as illustrated in Fig. 2, in order that they may co-operate to provide an open ended pocket of tapering form for the

purpose of conforming to the tapering contour of a steering wheel spoke, and in a manner to have wedging engagement therewith so as to be locked against accidental movement longitudinally on the spoke. The flanges 16 are sufficiently flexible to permit outward flaring thereof, an operation necessary to apply the flanges to the spoke. It will be understood that where the container and flanges are formed of rubber, the rubber will be vulcanized to a degree sufficient to cause the flanges to return to their original positions following flexing thereof when applying the same to the spoke.

As shown in Fig. 3, the upper end of the container is open to permit the insertion of the match box 18 to allow the projection of the match containing drawer 17 incident to removal of matches from the box. The drawer can be projected from the upper end of the container by extending the finger 70 through an opening 19 in the lower end of the box. Access to the scratching surface 20 of the match box is had through an opening 21 in one side of the container, and preferably the right side when the holder is in applied position.

In order to utilize the holder as an advertising novelty, provision is made for holding a card 22 therein and in a manner to display the advertising matter thereon. As shown 80 in Fig. 3 the container is provided interiorly, adjacent its top side with a pair of lips 23 extending inwardly from the opposite sides of the container and in spaced relation to the top thereof so as to provide intervening channels coextensive in length with the container in which are received the longitudinal edges of the card 22. The card is inserted through the upper open end of the container, and when in applied position the advertising 85 thereon is displayed through an opening 24 provided in the top of the container. Thus the advertising card is at all times in view of the operator of the vehicle.

Although I have herein shown and described only one form of match box holder embodying my invention, it is to be understood that various changes and modifications

may be made herein without departing from the spirit of the invention and the spirit and scope of the appended claim.

I claim as my invention:

- 5 An advertising display device comprising a container formed of elastic material and provided with spaced apart channels for the reception of the edges of a display card, and

spaced apart flanges formed as an integral part of the container and adapted to serve as 10 an attaching clamp to hold the container upon the spoke of a vehicle steering wheel, the container being open at one end so that a match box may be inserted in or withdrawn from the container.

ROBERT M. OSTRANDER.
